COMBINED HAND GRIP AND SPRAY NOZZLE FOR A SHOWERBATH

Clifford Lewis Barker, Cheltenham, England, assignor to
Walker Crossweller & Company Limited, Cheltenham,
England, a British company

Filed June 7, 1967, Ser. No. 7,389

Term of patent 14 years

(Cl. D23—35)

FIG.1.

FIG.2.

FIGURE 1 is a perspective view taken from the top one end and one side of a combined hand grip and spray nozzle for a showerbath, showing my new design;

FIGURE 2 is a perspective view taken from the bottom side and end opposite that shown in FIGURE 1.

I claim:

The ornamental design for a combined hand grip and spray nozzle for a showerbath, as shown.
